UNITED STATES PATENT OFFICE.

FRANCIS J. PLYM, OF NILES, MICHIGAN.

WINDOW CONSTRUCTION.

Application filed September 11, 1919. Serial No. 323,147.

To all whom it may concern:

Be it known that I, FRANCIS J. PLYM, a citizen of the United States, residing at Niles, in the county of Berrien and State of Michigan, have invented new and useful Improvements in Window Constructions, of which the following is a specification.

My invention relates particularly to improvements in the construction of window tracks and associated mechanism, whereby windows may be opened with a swinging motion in a vertical plane and yet may be weathertight when closed, and I have sought to improve upon the construction of the tracks, to improve upon the connection of the slidable elements with the track, to provide an improved weatherstrip for keeping wind and rain from entering between the sash and the frame, to improve in general upon existing structures of this character, and to accomplish such further objects, advantages, and capabilities as will later more fully appear.

With these and other incidental objects in view, I have devised the structure shown in the accompanying drawings, in which Fig. 1 shows a vertical transverse section through an open window showing my construction applied.

Fig. 2 is a fragmentary elevation of the structure shown in Fig. 1 with part of the frame broken away and in section.

Fig. 3 is a perspective view of my improved track, showing the connections between the track and the window sash.

Figs. 4, 5, 6, 7 and 8 are detail cross-sections along the lines 4-4, 5-5, 6-6, 7-7, and 8-8 of Fig. 2 respectively.

Referring more specifically to these drawings, the window casing is denoted by the numeral 1, the sash by 2, and the track in general by 3. A link 4 is pivotally connected at one end to a block 10 secured to the edge of the sash 2, while its opposite end is pivoted at 9 to block 8. Intermediate the ends and nearer to the one last named is pivoted at 7 a link 5, whose opposite end is pivoted at 6 to a block 12 secured to track 3, as best shown in Fig. 6. At its upper edge, 50 sash 2 has secured thereto a metal strip 11, which is pivoted at one end to slidable block 11^a, which runs in guideway 17 of track 3, shown best in Fig. 3. The details of this construction are shown best in Fig. 4, where 55 metal strip 11 is shown connected to block 11^a by a rivet 11^b, the block being embossed

so that its external face is just flush with the external face of the track.

Secured to the edges of the sash 2 are weatherstrips 13 having reversely bent edges 14 and 15, the former adapted to co-operate with track 3 to form a weathertight construction to keep wind and water from entering between the sash and track, and the latter cooperating with window stops 16 to 60 from another weather tight connection. The edges 15 enter into a groove or grooves formed within or between stops 16, and, being resilient, a close fit is necessarily secured between the parts at this point. Part 14, 70 being resilient, also, is bent slightly when it comes into contact with track 3 to form a tight but yielding joint when the window is closed. It will be noticed that this weatherstrip not only helps to form watertight 75 joints with the window stops and track, but furnishes also a resilient means to assist in keeping the window from rattling in strong winds.

Referring to Figs. 3 and 4, it will be seen 80 that track 3 comprises a hollow guideway 17, whose edges 18 form overhangs which are bent sharply outwardly in extensions 19 and 20, which are then bent away from the face which is to be directed toward the sash, 85 forming rearwardly extending side pieces 21 and 22. Part 22 is then bent laterally to form the edge strip 23 provided with holes for the reception of screws by means of which the track is fastened to the window 90 frame. This edge strip 23 has the securing screws covered by window stop pieces 16 to more securely fasten the track in place and also to hide the screws. The sheet metal of which track 3 is made is resilient, and therefore yields to cause the track to cooperate 95 with part 14 in forming a tight but yielding connection between the sash and the frame.

It is noted that part 21 of track 3 fits 100 closely against the wooden strip 21' of the window frame, thereby forming a tight joint to prevent snow, rain, or dust from getting between the woodwork and the track.

From this description it will be seen that grooved track 3 with its slot facing the sash serves as a guideway for slidable blocks 8 and 11^a; that, because of its resiliency, it cooperates with the weatherstrip on the edge 110 of the sash to keep out wind and rain; also because of its resiliency, it will help the

weatherstrip in compensating or swelling and contracting of the sash and frame as the same gets wet and dries out, and also because of its resiliency, a close but sufficiently yielding connection between the sash and frame is formed to avoid any straining of parts when opening and closing the window.

In operation, when the sash is pushed outwardly at the bottom, it carries with it the upper end of link 4, and because of the pivotal connection of link 5 at points 6 and 7, the lower end of link 4 is caused to move upwardly, carrying with it, in guideway 17, the block 8. At the same time, the upper edge of the sash attached to block 11^a moves downwardly, carrying said block downwardly along guideway 17. The operation of the device is very much improved by having the hollow track and the blocks or shoes running in the opening of the track.

It should be noted that this device may be installed by attaching block 10 and strip 11 to the edge of the sash and then placing this whole assembly in place within the window frame, after which screws are inserted in the holes in the edge strip 23 of track 3 and window stops 16 are put on to finish the installation. This method of assembly and installation is much simpler than previous methods and makes it possible for the work to be done quickly and easily.

Though I have shown and described in considerable detail the preferred form of my invention, this is not to be construed in a limiting sense, the same being done for the purpose of enabling one skilled in the art to which this invention pertains to construct and use the same.

Having now described my invention, I claim:

1. A track for a window construction comprising a hollow guideway having overhangs within which blocks may slide and be retained by the overhangs of the guideway, extensions from the overhangs extending laterally beyond the guideways, and side pieces extending rearwardly from the said extensions, one of which side pieces serves as attaching means or holding the track to a window frame.

2. A track for a window construction comprising a hollow guideway having overhangs and within which blocks may slide and be retained by the overhangs, lateral extensions from the overhangs, and side pieces rearwardly extending from said lateral extensions, one of said side pieces serving as attaching means for holding the track to a window frame, said last-named side piece being resilient whereby the guideway may be resiliently supported upon the frame for lateral movement under pressure.

3. In a window construction, a resilient hollow track supported by one edge for

slight lateral resilient movement, in combination with a sash having a metal weatherstrip secured to an edge thereof, said weatherstrip having an edge curved over to closely engage the track and prevent the entrance of wind and water.

4. In a window construction having a frame and a sash, in which the sash is adapted to swing outwardly, parallel to a vertical plane, a hollow track resiliently mounted upon the frame and having a slot facing the sash, a block rigidly mounted in the track and a pair of blocks slidably mounted in the track, one near the bottom and one near the top thereof, one of such slidable blocks being pivotally connected through the slot to the sash, and a link pivotally connecting the sash and the other slidable block and pivotally connected by means of a link to the fixed block.

5. In a window construction having a frame and a sash, in which the sash is adapted to swing outwardly, parallel to a vertical plane, a hollow track having a flange whereby it is resiliently mounted upon the frame and having a slot facing the sash, a block rigidly mounted in the track and a pair of blocks slidably mounted in the track, one near the bottom and one near the top thereof, one of such slidable blocks being pivotally connected through the slot to the sash, and a link pivotally connecting the sash and the other slidable block and pivotally connected by means of a link to the fixed block, said sash and track with their connections being assembled as a unit and placed in the frame.

6. In a window construction having a frame and a sash, in which the sash is adapted to swing outwardly, parallel to a vertical plane, a hollow track having a flange whereby it is resiliently mounted upon the frame and having a slot facing the sash, a block rigidly mounted in the track and a pair of blocks slidably mounted in the track, one near the bottom and one near the top thereof, one of such slidable blocks being pivotally connected through the slot to the sash, and a link pivotally connecting the sash and the other slidable block and pivotally connected by means of a link to the fixed block, said sash and track with their connections being assembled as a unit and placed in the frame, there being window stops to cover the track securing means and serve as abutments against which the sash may swing.

In witness whereof, I hereunto subscribe my name to this specification in the presence of two witnesses.

FRANCIS J. PLYM.

Certificate of Correction.

It is hereby certified that in Letters Patent No. 1,432,896, granted October 24, 1922, upon the application of Francis J. Plym, of Niles, Michigan, for an improvement in "Window Constructions," errors appear in the printed specification requiring correction as follows: Page 1, line 66, for the word "from" read *form*; page 2, line 50, claim 1, for the word "or" read *for*; and that the said Letters Patent should be read with these corrections therein that the same may conform to the record of the case in the Patent Office.

Signed and sealed this 5th day of December, A. D., 1922.

[**SEAL.**]

KARL FENNING,

Acting Commissioner of Patents.
